UNITED STATES PATENT OFFICE.

OTTO S. BEYER, OF BROOKLYN, NEW YORK, ASSIGNOR, BY MESNE ASSIGNMENTS, TO
E. W. BLISS COMPANY, OF BROOKLYN, NEW YORK, A CORPORATION OF DELAWARE.

RADIATOR.

Application filed August 1, 1924. Serial No. 729,522.

This invention relates to improvements in radiators and more especially light gauge metal radiators, and aims to provide improvements therein.

5 In the construction of these light gauge metal radiators, sheet metal has commonly been used, one or more pieces of the sheet metal being used to form a section. Seams of considerable length are required to unite 10 the meeting edges of the sheet or sheets of metal forming each section, and the production of an enduring leak-tight seam has been either unsatisfactory or costly.

The present invention provides a radiator 15 simulating the shape and form of the usual house-heating radiator, which is practically seamless, being formed of tube-stock, and which in thin gauge metal and substantially without seams, avoids the objection to seams 20 encountered in radiators formed of light gauge sheet metal.

An embodiment of the invention is illustrated in the accompanying drawings, in which 25 Fig. 1 is a side elevation, (with parts in section) of said embodiment.

Fig. 2 is an end elevation thereof.

Fig. 3 is a top plan view (with parts in section).

30 Figs. 4 and 5 are detail views.

Referring to said drawing, numeral 10 designates a tube, conveniently of light gauge sheet metal, such as 20 B. & S. gauge or even lighter, which is bent into the form 35 of a coil 12 comprising a plurality of complete bends or sections 14. Each complete bend or section comprises two vertical legs 16, 17 and top and bottom portions 19 and 20. The legs 16 and 17 and the top portion 40 19 of each bend or section 14 are preferably non-spiral, the legs being straight up and down and the top portion 19 straight across from one leg to the other. The pitch or cross-over from one bend or section 14 to

45 another is preferably through the bottom portion 20 of each bend (or common to two bends) which is arranged diagonally. The cross-over could obviously be at the top instead of at the bottom, as shown and described.

The legs 16, 17 are preferably flattened as indicated at 24 in such manner that the flattened faces of each bend or section are opposite one another; thereby providing for

a good circulation of air between the radiator sections.

The bends or sections 14 are also preferably connected otherwise than through the cross-over bottom portion 20, for the purpose of rigidity, and are also preferably laterally connected in such manner that the interiors of the sections are in additional communication, for the purpose of better circulation or distribution of the heating fluid therein. To this end, the top and bottom portions 19 and 20 may be connected by short tubes or nipples 25, 26. The top and bottom portions 19 and 20 have openings 27, 28, 29, 30, for receiving the ends of the nipples 25, 26, and for convenience in manufacture the sides of the top and bottom portions immediately around said openings 27, 28, 29, 30, are flattened, as indicated at 33, 34. There is preferably a screw-threaded connection between the nipples 25, 26 and 65 the sections 14, and as the metal of the sections 14 is or may be too thin for the formation of adequate screw-threads therein, the openings 27, 28, 29, 30 are preferably bushed 70 or rimmed with a heavier ring of metal 37 75 which is fastened thereto by seaming or crimping, as indicated in Fig. 5, and threads 38 are formed in the ring 37.

The ends 40, 41 of the tube 10 are closed in suitable manner. The ends are preferably flattened so that the edge portions lie together, and the length of the edges being short it is neither difficult nor expensive to close the ends by practically any usual means. The preferred means is a strip of 85 relatively heavy metal 45, which is seamed or crimped on the ends 40, 41, as indicated in Fig. 4. Such a joint will be durable, and not affected by strains, shocks, etc., to which the radiators may be subjected, as is the case 90 with long seams, as for example those in sheet metal radiators.

Method.—According to the present method a piece of tube stock 10, preferably of light gauge metal, and of sufficient length to form 100 a plurality of complete bends, or "sections", is taken and bent into the form of a coil 12 comprising a number of complete bends or convolutions 14. The legs 16, 17 are preferably formed straight up and down, the pitch 105 or cross-over from one section or complete bend 14 to another being provided by bending the top or bottom portion 19, 20, here

shown as the bottom portion 20, diagonally. The top or bottom portions 19, 20 or both are provided with openings 27, 28, 29, 30, and one section is joined to another by 5 nipples 25, 26 for example. The parts of the tube portions 19, 20 in which the openings are formed are preferably formed with flat portions 33, 34. The ends 40, 41 of the tube 10 are closed in suitable manner, as by 10 clamping between the edges of a strip of metal 45. The adjacent sides of the leg portions 16, 17 are preferably flattened, as indicated at 24.

Modifications of the construction herein 15 specifically illustrated and described may be made without departing from the idea of invention. Variations in the mode of procedure specifically described may be made without departing from the invention.

20 What is claimed is:

1. A radiator comprising a plurality of tubular sections or bends formed from tubular stock, means placing said sections in series communication, and means placing 25 said sections in lateral communication.

2. A radiator comprising sections each comprising a tube bent to form tubular U-shaped portions having vertical legs and a cross tubular portion connecting a leg in 30 each of two adjacent U-shaped portions.

3. A radiator comprising sections each comprising a tube bent to form tubular U-shaped portions, and a cross tubular portion connecting a leg in each of two adjacent U-shaped portions, and means connecting 35 adjacent sections for communication at the end opposite said cross-portion.

4. A radiator comprising a tube bent into 40 a coil comprising a plurality of complete turns or bends, and having lateral means of communication between adjacent bends, said bends being flattened crosswise of the coil.

45 5. A radiator, comprising a tube bent in the form of a coil, each complete bend comprising two vertical non-spiral legs and top and bottom portions one of said portions connecting said legs, and the other portion of which runs diagonally and connects one complete bend with another.

50 6. A radiator, comprising a tube bent in the form of a coil, each complete bend comprising two vertical non-spiral legs and top and bottom portions one of said portions connecting said legs, and the other portion of which runs diagonally and connects one complete bend with another, said legs being flattened.

55 7. A radiator, comprising a tube bent in the form of a coil, each complete bend com-

prising two vertical non-spiral legs and top 60 and bottom portions one of said portions connecting said legs, and the other portion of which runs diagonally and connects one complete bend with another, and means connecting the complete bends at top and bottom. 65

8. A radiator, comprising a tube bent in the form of a coil, each complete bend comprising two vertical non-spiral legs and top and bottom portions one of said portions connecting said legs, and the other portion of 70 which runs diagonally and connects one complete bend with another, and means connecting the complete bends at top and bottom, said means comprising short tubes or nipples fitting openings in said bends. 75

9. A radiator, comprising a tube bent in the form of a coil, each complete bend comprising two vertical non-spiral legs and top and bottom portions one of said portions connecting said legs, and the other portion of 80 which runs diagonally and connects one complete bend with another, and means connecting the complete bends at top and bottom, said means comprising short tubes or nipples fitting openings in said bends, said diagonal portion of the bend having a portion in a plane at right angles to the axis of the coil. 85

10. A radiator, comprising a tube bent in the form of a coil, each complete bend comprising two vertical non-spiral legs and top 90 and bottom portions one of said portions connecting said legs, and the other portion of which runs diagonally and connects one bend with another, and means connecting the complete bends at top and bottom comprising 95 short tubes or nipples fitting openings in said bends, said legs being flattened.

11. A radiator comprising a plurality of tubular sections or bends having legs and top and bottom portions formed from tubular 100 stock, means placing said sections in series for fluid communication and means providing a lateral connection for fluid communication between one portion of one section and the corresponding portion of the adjacent section. 105

12. A radiator comprising a plurality of tubular sections or bends having legs and top and bottom portions formed from tubular 110 stock, means placing said sections in series for fluid communication and means providing a lateral connection for fluid communication between the top and bottom portions of one section and the corresponding portions of the adjacent section. 115

In witness whereof, I have hereunto signed my name.

OTTO S. BEYER.
